PICKER STICK CHECK

Carl D. Brown, Hopedale, Mass., assignor to
 Draper Corporation, Hopedale, Mass., a corporation of Maine

Application June 10, 1939, Serial No. 279,537

7 Claims. (Cl. 139—165)

The present invention pertains to fly shuttle looms and more particularly relates to picker stick checking means for such looms.

Looms of the type to which my invention applies commonly include a reciprocating lay comprising a lay beam and a rocker shaft about which the lay beam oscillates, a picker stick carried by the lay, a picker stick check comprising a suitable device usually in the form of a flexible 10 check strap encircling the picker stick and moved by the latter at each end of its sweep, and friction members for applying friction to the check to resist movement thereof by the picker stick. As previously constructed, such friction members 15 have been made adjustable, but the construction provided is difficult to adjust with any degree of accuracy, and is uncertain and unreliable in operation. Furthermore, such friction members were so constructed that all parts thereof move 20 with the rapidly moving lay and hence are not accessible for adjustment when the loom is running.

I find that, particularly on high speed looms, movement of the shuttle is very sensitive to the 25 action of the picker stick check or check strap, and that if the shuttle is to operate properly the friction on the check strap must be very accurately adjusted. In this connection, it is highly desirable that said friction be adjustable while 30 the loom is in operation, so that the movements of the shuttle may be observed simultaneously with the making of the adjustment.

It is accordingly a principal object of the present invention to provide a loom having a lay, 35 picker stick and check strap as aforesaid, a suitable friction member having a friction surface engaged by the check strap, and an eccentric for holding the check strap against said friction surface, which eccentric shall be rotatively adjustable relative to said friction surface, thereby providing a friction means which may be easily and accurately adjusted and which is reliable in operation.

A further object of the invention is to provide 45 a loom having a lay, including lay beam and rocker shaft, a picker stick, and a check strap, as aforesaid, friction means for frictionally resisting movement of the check strap, and means for adjusting the friction means, which adjusting 50 means shall be carried by the lay adjacent the axis of the rocker shaft thereof whereby the said means shall remain substantially stationary during operation of the loom, to render the adjusting means accessible while the loom is running.

The foregoing and other objects of the invention are accomplished in the construction illustrated on the accompanying drawings, of which:

Figure 1 is an end view in elevation of part of a loom having the preferred embodiment of my invention applied thereto;

Fig. 2 is a front view of the same;

Fig. 3 is a plan view, to a larger scale, showing part of the lay and picker stick check of Figs. 1 and 2;

Fig. 4 is a view, partly in plan and partly in section, showing the parallel and certain parts of the check adjusting means of said Figs. 1 and 2;

Fig. 5 is a view in cross-section taken approximately on line 5—5 of Fig. 4; and

Fig. 6 is a detail view of a part of said picker stick check.

The loom shown on the drawings includes parts and mechanisms which are of suitable usual construction forming no part of the present invention and which are accordingly not shown or described. Part of the construction that is shown on the drawings is also old, this part including the left hand loom side 1, and the lay which includes a lay beam 2 and a rocker shaft 3. The rocker shaft 3 is journaled in the loom frame and the lay reciprocates or oscillates on the rocker shaft so that the lay beam reciprocates toward and from the front of the loom as is well known in the art, the front being at the right on Fig. 1.

A supporting member 4, commonly known as a parallel, is mounted upon and fixed to the end of the rocker shaft 3. The parallel 4 has a flat surface 5 upon which a curved shoe 6 rocks, a picker stick 7 being fixed to said shoe. A spring return device 8 is connected to the picker stick for yieldingly urging the stick outwardly of the loom, which is toward the left on Fig. 2. The picker stick is thus carried by the lay. The picker stick, with shoe 6 thereon, rocks inwardly of the loom to pick the shuttle, also not shown. This picking mechanism as thus far described is of usual construction.

The aforesaid picking movement of the picker stick is a very rapid movement, wherefore appreciable force is required to check the stick at the end of such movement. The return movement of the picker stick is not so rapid, but this return movement must be checked to impart a checking action to the shuttle as the latter returns toward the picker stick shown on the drawings. Various picker stick check devices have been proposed, but the type generally used includes a flexible

check strap such as leather strap 9 to which friction is applied.

The check strap 9 is bent to form a flattened loop which encircles the picker stick 7. The ends 5 of the strap, at one side of the loop, are fixed to the lay as by being bolted to a bracket 10 on the lay beam 2, a bolt 11 being shown for this purpose. The check strap is thus supported directly beneath the lay beam and moves forwardly and 10 rearwardly with the latter. Any suitable friction member may be provided for applying friction to the other side of the loop, to frictionally resist movement of the check strap by the picker stick and thereby check the picker stick. As shown, 15 such friction member comprises a bracket 12 which is bolted to the lay beam and provided with fingers 13 each having a friction surface 14. The friction surfaces 14 are in engagement with one face of the check strap. The check strap is 20 held against the friction surfaces 14 by a member which, in accordance with one aspect of my invention, consists of a manually adjustable eccentric.

The aforesaid eccentric in its preferred form 25 consists of a hollow cast iron shell 15 which has a surface 16 engaging the opposite face of the check strap 9 from surfaces 14. This eccentric has hub portions by which it is fixed upon the upper end of a rod 17. The rod 17 is eccentric of 30 the surface 16 and extends vertically. The rod is journaled in bearings 18 and 19 formed in the bracket 12, whereby the rod and eccentric are supported by the lay. Rotation of the rod 17 and eccentric 15 serves to adjust the eccentric relative 35 to the friction surfaces 14 and to thereby vary the amount of friction that is applied to the check strap.

I find that an eccentric, such as the eccentric 40 15 just described, is a substantial improvement over prior devices for holding a check strap against a friction surface, because it is more reliable in operation and may easily be accurately adjusted. This construction is accordingly of value when used with any suitable means for holding the eccentric in adjusted position. I have, however, devised a novel means for such 45 purpose, which means is located adjacent the axis of the rocker shaft 3, whereby it remains substantially stationary during operation of the loom 50 and may accordingly be manipulated while the loom is in operation. To this end, the rod 17 is extended downwardly to a point nearly in axial alignment with the rocker shaft, and manually operable means for turning the rod to adjust the eccentric, as well as said holding means, are located at the lower end of the rod.

In the embodiment shown, the lower end of the rod 17 is journalled in a bearing member 20 which is bolted to a lug 21 projecting forwardly from the parallel 4. An arm 22 is fixed to the rod 17 below the lug 21 as by means of a nut 23. This arm extends horizontally and forms a handle which may be engaged by the operator's hand or foot for turning the rod and eccentric. A latch lever 24 is pivoted to the arm 22 at 25 and has an end 26 for engagement with any of a plurality of radial notches 27 formed in the member 20. A spring 28 normally holds the end 26 in engagement with the desired notch 27.

Upon releasing the end 26 from its notch 27, the 70 arm 22 may be turned to thereby adjust the eccentric 15 relative to the friction surfaces 14. The arm 22 being carried by the lay adjacent the axis of the rocker shaft, the arm remains substantially stationary during operation of the loom and

accordingly may be manipulated while the loom is running. Upon releasing the latch 24 of the arm 22, the end 26 of the latch engages in a notch 27 and holds the arm and eccentric in adjusted position.

Having fully disclosed the preferred embodiment of my invention, I claim:

1. In a loom, the combination of a reciprocating lay, a picker stick carried by said lay, a flexible check strap forming a loop encircling 10 said picker stick, means fixing one side of said loop to the lay, a fixed friction member having a friction surface engaging the other side of said loop, a vertical rod rotatably supported by the lay on the opposite side of said strap from said surface, an eccentric fixed on said rod and engaging said check strap and holding the latter against said friction surface, said eccentric being manually rotatably with said rod to adjust the position of the eccentric relative to said friction surface, and manually operable means for fixing said rod and thereby said eccentric in adjusted position.

2. In a loom, the combination of a reciprocating lay, said lay comprising a lay beam and a 25 rocker shaft about which said lay beam oscillates, a picker stick carried by said lay, a flexible check strap forming a loop encircling said picker stick, an adjustable friction device for frictionally resisting movement of said check strap by said 30 picker stick, and a manually operable adjusting member connected to said device for adjusting the latter, said member being carried by the lay adjacent the axis of said rocker shaft whereby the member remains substantially stationary during 35 operation of the loom.

3. In a loom, the combination of a reciprocating lay, said lay comprising a lay beam and a rocker shaft about which said lay beam oscillates, a picker stick carried by said lay, a flexible check 40 strap forming a loop encircling said picker stick, an adjustable friction device for frictionally resisting movement of said check strap by said 45 picker stick, said device comprising a friction member carried by said lay beam and engaging said check strap and an adjustable member for holding said check strap against said friction member, an adjusting arm carried by said lay adjacent the axis of said rocker shaft, and connections from said arm to said adjustable member for adjusting the latter from said arm.

4. In a loom, the combination of a reciprocating lay, said lay comprising a lay beam and a rocker shaft about which said lay beam oscillates, a picker stick carried by said lay, a flexible check 55 strap forming a loop encircling said picker stick, means fixing one side of said loop to the lay, a friction member engaging the other side of said loop, a rotatively adjustable eccentric for holding said check strap against said member, and manually operable means supported in a 60 relatively stationary position and connected to said eccentric for adjusting the latter.

5. In a loom, the combination of a reciprocating lay, said lay including the usual lay beam and 65 rocker shaft, a picker stick carried by said lay, a flexible check strap forming a loop encircling said picker stick, means for supporting said check strap beneath said lay beam, a friction member for frictionally resisting movement of 70 said check strap, a vertical rod having an eccentric for holding said check strap against said friction member, and manually operable means connected to said rod for rotating the latter and thereby adjusting said eccentric relative to 75

said friction member, said means being supported by the lay adjacent the axis of said rocker shaft whereby said means remains substantially stationary during operation of the loom.

- 5 6. In a loom, the combination of a reciprocating lay, said lay including the usual lay beam and rocker shaft, a picker stick carried by said lay, a flexible check strap forming a loop encircling said picker stick, means for supporting said 10 check strap beneath said lay beam, a friction member for frictionally resisting movement of said check strap, a vertical rod having an eccentric at its upper end for holding said check strap against said friction member, said rod extending downwardly to a point adjacent the axis of said rocker shaft, and manually operable means 15 on the lower end of said rod for rotating said rod and thereby said eccentric, to adjust the eccentric relative to said friction member.

7. In a loom, the combination of a reciprocating lay, said lay including the usual lay beam and rocker shaft, a picker stick carried by said lay, a flexible check strap forming a loop encircling said picker stick, means for supporting 5 said check strap beneath said lay beam, a friction member for frictionally resisting movement of said check strap, a vertical rod rotatably supported on said lay, an eccentric fixed on the upper end of said rod and engaging said check strap and 10 holding the same against said friction member, said rod extending downwardly to a point adjacent the axis of said rocker shaft, a manually operator arm on the lower end of said rod for rotating said rod to thereby adjust said eccentric 15 relative to said friction member, and latch means for fixing said arm and thereby said rod and eccentric in adjusted position.
